SPECIFICATION forming part of Design No. 24,098, dated March 12, 1895.

Application filed February 4, 1895. Serial No. 537,298. Term of patent 8½ years.

To all whom it may concern:

Be it known that I, JOHN MATTHEWS, a subject of the Queen of Great Britain, residing at Bridgenorth, in the county of Salop, England, 5 have invented and produced a new and original Design for a Carpet, of which the following is a specification, reference being had to the accompanying drawing, making a part of the same, and which is sufficient to enable others 10 skilled in the art to make and use my invention.

My design consists, first, of a body A, ornamented by two ornamental figures, on a clouded ground as shown in the drawing; 15 second, of a border B, consisting of a solid color top margin, two ornamental figures, and a narrow ornamental cross-stripe, composed of squares and diamonds, the whole on a clouded

ground as shown in the drawing; and, third, consisting of the combination of body A and border B, as shown in the drawing. 20

What I claim as new, and desire to secure by Letters Patent, is—

1. In a design for a carpet, the body A substantially as shown. 25

2. In a design for a carpet, the border B substantially as shown.

3. The design for a carpet, consisting of body A, and border B, substantially as shown.

JOHN MATTHEWS.
